US0D1086404S

(12) **United States Design Patent** (10) **Patent No.:** **US D1,086,404 S**
(45) **Date of Patent:** **** Jul. 29, 2025**

(54) **FAUCET**

(71) Applicant: **Kohler Co.**, Kohler, WI (US)

(72) Inventors: **Jean-Hugues Soulier**, Paris (FR);
Ferran Serra Sola, Paris (FR)

(73) Assignee: **KOHLER CO.**, Kohler, WI (US)

(**) Term: **15 Years**

(21) Appl. No.: **29/852,883**

(22) Filed: **Sep. 9, 2022**

Related U.S. Application Data

(60) Continuation of application No. 29/832,107, filed on Mar. 24, 2022, now Pat. No. Des. 964,525, which is a division of application No. 29/794,354, filed on Jun. 11, 2021, now Pat. No. Des. 950,682, which is a division of application No. 29/658,287, filed on Jul. 30, 2018, now Pat. No. Des. 925,703, which is a division of application No. 29/641,526, filed on Mar. 22, 2018, now Pat. No. Des. 901,643, which is a division of application No. 29/595,301, filed on Feb. 27, 2017, now Pat. No. Des. 823,441.

(57) **CLAIM**

The ornamental design for a faucet as shown and described.

DESCRIPTION

FIG. 1 is a top, front, right perspective view of the claimed design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The dashed broken lines depict portions of the faucet that form no part of the claimed design. The dash-dot broken lines represent the bounds of the claim and form no part of the claimed design.

1 Claim, 4 Drawing Sheets
